UNITED STATES PATENT OFFICE.

DENNIS P. BROPHY, OF NOKOMIS, ILLINOIS.

BAG-LOCK.

SPECIFICATION forming part of Letters Patent No. 331,473, dated December 1, 1885.

Application filed June 17, 1885. Serial No. 168,964. (Model.)

To all whom it may concern:

Be it known that I, DENNIS P. BROPHY, of Nokomis, Montgomery county, Illinois, have invented a new and Improved Mail-Bag Lock, 5 of which the following is a full, clear, and exact description.

The object of my invention is to provide a new and improved mail-bag lock which is strong and durable, safe and reliable.

10 The invention consists in the combination, with a lock-casing having two apertured longitudinal partitions, of bars having lugs which can be passed through the apertures in the partitions, springs acting on the bars, and a top plate having an apertured rib fitting between the partitions of the casing.

The invention also consists in parts and details and combinations of the same, as will be fully set forth hereinafter.

15 Reference is to be had to the accompanying drawings, forming part of this specification, in which similar letters of reference indicate corresponding parts in all the figures.

Figure 1 is a face view of my improved mail-bag lock. Fig. 2 is a front view, the front plate being removed and parts being in section. Fig. 3 is a longitudinal sectional view of the same. Fig. 4 is a cross-sectional view.

The lock-casing A is provided with the two 20 longitudinal partitions B, each having a recess, C, in its bottom part, at the middle, and a notch, C', extending from the top edge to the recess C. Against the outer edge of the partitions B the locking-bars D are pressed by bow-springs E, interposed between the outer sides of the locking-plates and the inner surfaces of the sides of the casing. The bars B have locking-lugs F, which are adapted to pass through apertures G in the partitions B, and have beveled ends. Each plate D has a flat lug, H, at its bottom and middle, which lugs have V-shaped recesses H', the recesses of the two lugs facing each other. A pin, K, projects upward from the bottom of the casing, midway between the partitions B, and serves to guide and hold the end of the key L, having two opposite bits, M. The front plate, N, has a longitudinal central rib, O, on its under side, which rib fits between the partitions B and 35 has a series of apertures, P, for receiving the lugs F on the bars D, and a recess, Q, in its bottom edge at the middle for permitting the bits of the key to turn. The rib is beveled 40

on its edge. The plate N and rib O have a key-slot, R. On the top of the plate N undercut ribs S are formed for receiving and holding a ticket, T. A sliding plate, U, having one end rabbeted to hold the end edge of the ticket T, as shown in Fig. 3, is provided on its under side with a dovetailed lug, V, which 45 slides in a dovetailed recess, W, in the top of the plate N. The plate U has a finger-recess, U', in its top.

The lock-casing A is fastened to one flap, I, of the mail-pouch or other pouch, and the top 50 plate, N, to the other flap, I'.

The operation is as follows: The plate N is pressed on the casing A, the rib O passing between the partitions B. The inner beveled edge of the rib O strikes the beveled lugs F, 55 and the same are then forced through the apertures P by the springs E, whereby the two parts of the lock are held together. The slide U covers the key-hole.

To open the lock, the slide U is withdrawn, 75 the key is inserted and given a quarter-turn on its axis. The bits M, acting on the lugs H, press the bars D from the partitions B, whereby the lugs F are moved from the rib O, thus permitting the same and the plate N to be 80 withdrawn.

I do not claim in this application the ticket-holding devices, as I propose making the same the subject of a separate application.

Having thus described my invention, I claim 85 as new and desire to secure by Letters Patent—

1. In a mail-bag lock, the combination, with a casing having apertured longitudinal partitions, of bars having lugs which pass through the apertures in the partition, springs acting 90 on the bars, and of a top plate having an apertured rib on its under side which fits between the partitions in the casing, substantially as herein shown and described.

2. In a mail-bag lock, the combination, with 95 the casing A, having the apertured partitions B, of the bars D, having the beveled lugs F and the flat middle lugs, H, the springs E, and the top plate, N, having the beveled apertured rib O, substantially as herein shown and 100 described.

DENNIS P. BROPHY.
